UNITED STATES PATENT OFFICE

WASHINGTON IRVING BULLARD, OF BOSTON, MASSACHUSETTS, ASSIGNOR TO E. H. JACOBS MFG. CO., INC., OF DANIELSON, CONNECTICUT, A CORPORATION OF CONNECTICUT

LUG STRAP AND METHOD OF MAKING

Application filed May 26, 1928. Serial No. 280,808.

My present invention relates to lug straps for looms, and more particularly to an improved lug strap and method of making the same.

5 Lug straps, as made at the present day, are invariably made of layers of ticking or duck cemented together, and the better forms are provided with a rounding bow so as to better receive the picker stick and to withstand the 10 pounding that so soon destroys the usefulness of the lug strap. It has been found that not only does the lug strap wear out at the bow but, because of the blows imparted at the picker stick, there is a tearing out of the 15 material of the lug strap at the bolt slot and a large percentage of lug straps are destroyed for this reason long before they have been worn out at the bow. It has been proposed to reinforce the lug straps by placing within the 20 fabric body a core of fibrous material, such as vulcanized fibre, and in this case the vulcanized fibre extends throughout the entire length of the lug strap. Such construction, however, is not satisfactory as the vulcanized fibre tends to break down under repeated 25 blows and also there is a marked tendency on the part of the fabric to separate from the vulcanized fibre regardless of the character of the adhesive used during the process of 30 manufacture. A difficulty attendant the manufacture of lug straps is that while they must be strong and able to withstand repeated blows from the picker stick, yet they must be light and the various attempts, therefore, 35 that have been made to reinforce the lug straps, such as the insertion of a vulcanized fibre core, has rendered the lug straps too heavy to be of service.

In my present invention, I have obviated 40 the defects of prior devices, and have produced an improved lug strap provided with reinforcements at the bow and at the bolt slots, which construction makes a lug strap that is amply strong for any purpose for 45 which it may be used and yet is light enough to meet all the requirements in the textile art. With the addition of the reinforcing member at the bow, I am enabled to not only make this bow section strong but the bow is larger 50 and more resilient, and further, with the re-

inforcing at the bolt slots, there is now no tendency for the bolt slots to pull out. Where a heavy lug strap is permitted, I may utilize a plurality of threads of fabric or a plurality of rods of metal, such as spring steel, phosphor bronze, brass, or the like, running longitudinally the entire length of the lug strap which gives it enormously additional strength without additional weight. In addition to my 55 improved lug strap for looms as an article of manufacture, I believe the method by which the same is manufactured to be distinctly new and I desire to claim the method of manufacture herein. Further, it is believed that the method of manufacture is so closely allied with the article manufactured thereby as to have these two items constitute a single unitary invention, and therefore, 60 claims for both the article and the method of manufacturing the same are incorporated 65 herewith.

An object of my invention, therefore, is an improved lug strap for looms.

Another object is an improved method of 70 manufacturing lug straps for looms and the like.

In the accompanying drawings illustrating 75 preferred embodiments of my invention,

Fig. 1 is a developed view of the elements comprising a lug strap manufactured according to my improved method;

Fig. 2 is a view showing the developed form of lug strap illustrated in Fig. 1 rolled up and placed in position in a mold;

Fig. 3 is a sectional view on the line 3—3 of Fig. 2 showing the upper portion of the mold in position to form the inner surface of the lug strap;

Fig. 4 is a view similar to Fig. 1 and showing an improved form of reinforcing;

Fig. 5 is a plan view of a completed lug strap made either from the elements shown in Fig. 1 or the elements shown in Fig. 4;

Fig. 6 is a side elevation of Fig. 5;

Fig. 7 is a sectional view through a rolled up lug strap of the material shown in Figs. 1 and 4 and before being subjected to the molding action;

Fig. 8 is a sectional view on the line 8—8 of Fig. 5, and

Fig. 9 is a view similar to Fig. 8 but illustrating in cross section wires or threads indicated in Fig. 4 and extending longitudinally of the strap structure.

Referring to the drawings, and particularly Figs. 1, 2, and 3, 10 designates a layer of ticking or duck on which is superimposed, and in the relation shown, a layer of ticking or duck 11 and the layer 11 at each side thereof and arranged parallel thereto and in position to occupy a space in the completed lug strap occupied by the bolt slot has parallelly arranged layers of ticking or duck 12. Centrally arranged with respect to the layers 12 and resting on the layer 11 are rectangular layers 13 and 14 respectively. The above elements and the position thereof shown in Fig. 1 constitute practically the first step in the process or method of manufacturing a lug strap embodying my invention. The elements shown in Fig. 1 are now rolled or folded upon each other so that a cross sectional view through the center thereof will be similar to that shown in Fig. 7. The entire 25 rolled structure is saturated with an adhesive such as glue, or synthetic resin. A commercial form of synthetic resin is known as textolite and is made of laminated or macerated material and an adhesive thermo-plastic binder which hardens under heat. When the structure is in the rolled up position above described, it is placed in a mold 15 which has the shape in plan view as that illustrated in Fig. 2. The structure is then 35 subjected to heavy pressure and where bakelite or synthetic resin is used as the adhesive, to heat as well.

Referring to this figure, it will be noticed that the central portion thereof occupies a 40 space that is considerably wider than the remainder of the lug strap due to the presence in the rolled up material of the reinforcing layers 13 and 14. After being placed in the mold 15, a top plate 16 forming part 45 of the mold structure is placed over the lug strap structure as shown in Fig. 3, there being first placed and glued to the upper surface of the lug strap structure a layer 17 of leather or similar material. Fig. 3, which 50 shows a cross sectional view on the line 3-3 of Fig. 2 illustrates the reinforced portions as compared with the rest of the structure. Referring to such Fig. 3, it will be seen that the central portion is raised up to an extent 55 greater than any other part of the lug strap, while the end portions 18 are raised up but not to the extent of the central portion. On the contrary, the portions 19 intermediate the end portions 18 and the central portion 60 are and have practically the same cross sectional area as the older type of lug strap. This is so because such construction is sufficiently strong and yet not being subjected to blows or direct wear, reinforcing at these 65 points is not necessary.

After the materials shown in Fig. 1 have been subjected to the forming process as illustrated in Figs. 2 and 3, the partly finished lug strap is allowed to season and while still "green" or fresh, is folded into the form shown in Fig. 5, after which, or just prior to, the bolt slots 21 are formed in the ends 18. Referring to Fig. 8, it will be noted that the crowned portion of the bow has the covering leather 17 therefor following the contour thereof to the outer edges of the structure, so that a picker stick 22, as indicated by the dotted lines in Fig. 8, will be seen to strike the crown surface practically only at a single point, regardless of the relative positions of the picker stick and lug strap.

Referring now to Fig. 4, there is shown the layers 10, 11 and 12 similar in size and position and material to the corresponding layers 10, 11 and 12 in Fig. 1. The reinforcing layers 13 and 14 of Fig. 1 have been replaced by reinforcing layers 22—22 of oval or ovoid shape. A lug strap formed of the material just described with respect to Fig. 4, therefore, while resulting in a lug strap similar to that manufactured according to the description of Figs. 1, 2, and 3, will be slightly neater in appearance because of the absence of the sharp line of division between the centrally crowned portion and the reduced portions 19. In case it is desired to make an extremely strong lug strap and in which the question of weight is not controlling, I find it advantageous to roll up in the structure shown in Fig. 4, for example, rods 23 of a resilient or elastic material, such as steel, bronze, or the like, or may replace the same with cord or twine, as may be desired. The resulting structure is exceedingly strong and danger of pulling out at the bolt slots 21 is 100 practically negligible.

A lug strap manufactured according to my present invention has an increased bearing surface as compared with existing lug straps as well as having a reinforced and exaggerated cushion at the bow for engagement with the picker stick. Further, as the main danger to the lug strap is the pulling out at the bolt slots, my improved construction of narrower sides gives additional tensile strength to this portion of the article and with reinforced bolt slots, the danger of breakage at this point is 110 practically eliminated.

The application of pressure, forming, molding, and consolidating the entire set of layers, as well as the leather face 17, may be applied in any way desired, and may advantageously be so applied as to exert a greater compression along the edge portions around the bow, thus still further consolidating and 120 strengthening the wearing surface, considerably reenforcing the edge portions where the leather face 17 of the lug strap extends around the edge portion thereof. While I prefer to have the layers rolled, molded, and 125

compressed as herein described, it will be appreciated that I may unite and consolidate the same by any suitable application of pressure, whether by molds, dies, or otherwise.

5 My resultant structure produces a lug strap with reinforcements where needed at the bow portion and at the bolt slots, gives a wider and, therefore, a great wear resisting surface on the bows, and with the structure solidified through the application of pressure and the interrolling with suitable adhesive, results in an improved article of manufacture of greatly increased wearing capacity, and yet with an economical and practical construction.

10 Having thus described my invention, what I claim as new is:

1. That improvement in the art of manufacturing lug straps for looms and the like which consists in arranging a plurality of 20 layers in superimposed relation, placing thereon and adjacent either end thereof reinforcing layers, placing a plurality of reinforcing layers in substantially central position with respect to the end reinforcements 25 and forming the entire set of layers into a unitary structure.

2. That improvement in the art of manufacturing lug straps for looms and the like which consists in arranging a plurality of 30 layers in superimposed relation, adding reinforcing layers at the points occupied by the bow and bolt slots of the lug strap, impregnating the structure with adhesive material, rolling the superimposed layers of material into an elongated roll, placing the same in a mold and subjecting them to pressure to 35 form a crown portion at the central reinforcement and a reduced cross sectional area at the bolt slot portions.

40 3. That improvement in the art of manufacturing lug straps for looms and the like, which consists in arranging a plurality of layers in superimposed relation, adding reinforcing layers at the points occupied by the bow 45 and bolt slots of the lug strap, impregnating the structure with adhesive material, rolling the superimposed layers of material into an elongated roll, placing the same in a mold and subjecting them to pressure to form a 50 crown portion at the central reinforcement and a reduced cross sectional area at the bolt slot portions, forming bolt slots at the end reinforced portions and folding the completed structure into a U-shaped form.

55 4. That improvement in the art of manufacturing lug straps for looms and the like, which consists in arranging a plurality of layers in superimposed relation, adding reinforcing layers at the points occupied by the bow 60 and bolt slots of the lug strap, impregnating the structure with adhesive material, such as synthetic resin, rolling the superimposed layers of material into an elongated roll, placing the same in a mold and subjecting them to pressure and heat to form a crown portion at

the central reinforcement and a reduced cross sectional area at the bolt slot portions.

5 That improvement in the art of manufacturing lug straps for looms and the like, which consists in associating a plurality of 70 layers in superimposed relation, applying reinforcements adjacent each end, interrolling the same into the form of a lug strap, and subjecting the same to application of pressure to solidify and finish the strap.

6 That improvement in the art of manufacturing lug straps for looms and the like, which consists in associating a plurality of 75 layers in superimposed relation, applying reinforcing layers at the positions for the bow and bolt slots of the lug strap, impregnating the structure with adhesive material, rolling the same into an elongated roll, and thereupon subjecting said roll to an application of pressure to form a crown portion at the centre of 80 reinforced section and a suitable contour for the bolt slot sections.

In testimony whereof, I have signed my name to this specification.
